US0D1073807S

(12) **United States Design Patent** (10) **Patent No.:** **US D1,073,807 S**
(45) **Date of Patent:** **** May 6, 2025**

(54) **DRIVING SIMULATOR**

(71) Applicant: **Dr. Ing. h.c. F. Porsche**
Aktiengesellschaft, Stuttgart (DE)

(72) Inventor: **Salar Vakili**, Stuttgart (DE)

(73) Assignee: **Dr. Ing. h.c. F. Porsche**
Aktiengesellschaft (DE)

(**) Term: **15 Years**

(21) Appl. No.: **29/825,960**

(22) Filed: **Feb. 8, 2022**

(30) **Foreign Application Priority Data**

Aug. 25, 2021 (EM) 008661227-0001
Aug. 25, 2021 (EM) 008661227-0002

(57) **CLAIM**

The ornamental design for a driving simulator as shown and described.

DESCRIPTION

FIG. 1 is a perspective view of a driving simulator showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines immediately adjacent to the shaded areas depict the bounds of the claimed design, while all other broken lines are directed to environment.

1 Claim, 7 Drawing Sheets
